United States Patent Office.

EDMOND BOSDEVEX, OF PHILADELPHIA, PENNSYLVANIA.

Letters Patent No. 79,195, dated June 23, 1868.

IMPROVEMENT IN GRATES.

The Schedule referred to in these Letters Patent and making part of the same.

TO ALL WHOM IT MAY CONCERN:

Be it known that I, EDMOND BOSDEVEX, of Philadelphia, Pennsylvania, have invented an Improved Grate for Stoves, Ranges, &c.; and I do hereby declare the following to be a full, clear, and exact description of the same:

My invention consists of a permanent grate and a hinged grate, adapted to each other and to the fireplace of a stove or range, substantially as described hereafter, so that the space for containing the fuel may be expanded and contracted at pleasure, and so that the upper surface of the fuel may be always maintained in close proximity to the culinary vessels above the fireplace.

In order to enable others skilled in the art to make and use my invention, I will now proceed to describe its construction and operation, reference being had to the accompanying drawing, which forms a part of this specification, and in which—

Figure 1 is a vertical section of my improved grate for stoves, ranges, &c.

Figure 2, a plan view.

Figure 3, a transverse vertical section on the line 1 2, fig. 1, showing the movable portion of the grate lowered; and

Figure 4, the same, with the movable grate elevated.

Similar letters refer to similar parts throughout the several views.

A and A' represent the sides of the fireplace, and are made hollow in the present instance, so as to be serviceable as water-heaters.

In front of the fireplace, and between the sides A and A' of the same, is secured a grate, B, of the curved form represented in figs. 3 and 4; and at the rear of the fireplace is a grate, D, provided with projections a, one of which is adapted to a recess in the hollow side A, the other to a recess in the hollow side A' of the fireplace, to which the grate is thus so hinged that it can be lowered, as seen in fig. 3, or raised, as seen in fig. 4.

The rear of the grate B is made in the arc of a circle, of which the axis of the hinged grate D is the centre, so that no matter what may be the position to which the grate D has been adjusted, its lower edge is always in close proximity to the rear of the grate B.

To a lug, e, on one of the end bars of the grate, is hinged a link, f, having at its lower end an eye for receiving the end of a rod, by operating which, from the front of the fireplace, the grate D may be raised or lowered at pleasure, the link catching against any of the projections on a rack, h, secured to one of the sides of the fireplace, so that the grate will be maintained in the position to which it has been adjusted.

Other devices, equivalent to and as effective as that described for operating and retaining the grate, will suggest themselves; it does not, therefore, constitute an especial feature of my invention.

As seen in fig. 3, the space for the fuel has been expanded to its full extent, by depressing the grate D. It can be contracted, however, from time to time, as the fuel is consumed and decreases in quantity. The extent of the upper surface of the fuel is, however, not materially diminished by elevating the grate D; and this upper surface of the fuel, the most available for heating purposes, may always be maintained in close proximity to the culinary vessels above the fireplace.

The delay caused in cooking above ordinary fireplaces, owing to the necessity of supplying the sinking fire from time to time with fresh fuel, is obviated by the above-described invention, which possesses the further advantage of economizing fuel.

Although I have shown the permanent and hinged grates as being arranged between two hollow sides of a fireplace, it will be readily understood that they can be adapted to fireplaces of different styles without any difficulty.

I claim as my invention, and desire to secure by Letters Patent—

The combination of a permanent grate, B, and a grate, D, hung to the rear side of a fireplace, and capable of such adjustment that its front edge may be brought to any desired position on the grate B, for the purpose described.

In testimony whereof, I have signed my name to this specification in the presence of two subscribing witnesses.

EDMOND BOSDEVEX.
